MAILBOX

Joseph D. Price, Toledo, Ohio

Application April 18, 1950, Serial No. 9,295

Term of patent 7 years

(Cl. D74—9)

To all whom it may concern:

Be it known that I, Joseph D. Price, a citizen of the United States and a resident of Toledo, Lucas County, Ohio, have invented a new, original, and ornamental Design for a Mailbox, of which the following is a specification, reference being had to the accompanying drawing, forming a part thereof.

In the drawing:

I claim:

The ornamental design for a mailbox, as shown.
JOSEPH D. PRICE.
